UNITED STATES PATENT OFFICE.

BENJAMIN BRODIO, OF NEW YORK, N. Y., ASSIGNOR TO THE SUPERHEATER COMPANY, OF NEW YORK, N. Y., A CORPORATION OF DELAWARE.

APPARATUS FOR DRAINING AND CLEANING SUPERHEATERS.

Application filed August 20, 1921. Serial No. 493,900.

The invention relates particularly to superheaters of a construction to be described farther on, although its use is not confined to that class of structures, and has for its primary purpose the provision of apparatus with which moisture and other matter which may have accumulated in the tubes of the superheater may readily be removed before the boiler of which the superheater forms a part, or the superheater when it is separate from the boiler, is fired up. It is of use also for forcing water or other liquids through the superheater tubes to wash or clean them out; and such use of the apparatus is evidently not confined to superheaters but may occur in devices used for other purposes if their construction is otherwise adapted to it. While in the following description my invention is spoken of only in connection with superheaters, and its function only as related to one purpose, this is not to be interpreted as limiting it in these respects.

For an understanding of the invention the following description, to be read in connection with the accompanying drawings, will be sufficient. In the drawings, Fig. 1 is a cross-sectional view of a boiler and its setting, equipped with a superheater of the type to which my invention applies; Fig. 2 is a somewhat enlarged view illustrating a section taken on line 2—2 of Fig. 1, looking in the direction indicated by the arrows, my apparatus being shown in the position it occupies during use; Fig. 3 is a still more enlarged sectional view of my apparatus in the position it occupies in the superheater header during use, the section being taken on line 3—3 of Fig. 4; and Fig. 4 is a section on line 4—4 of Fig. 3.

The superheater with which my apparatus is to be used may be either independently fired or may be one installed in the same housing with a boiler. In the latter case the type of boiler it is installed in is immaterial as far as the use of my device is concerned. In the drawings I have illustrated the superheater as installed in a H. R. T. boiler. The housing enclosing it is designated by reference numeral 1. The boiler bears the number 2. 3—3 are the two headers of the superheater. To them are secured the superheater elements 4. 5 is the steam pipe delivering steam from the boiler to one of the headers. It is connected to the header by the elbow 6, which is provided with a valved drain

pipe 7. At the opposite end of the other header the flange 8 is provided for securing to the header the steam main which carries the steam to the point of use. This steam main is not shown, as it forms no part of my invention and has no connection with it. 8 is a flange to which is bolted the cover 8^b. If the connection to the steam main is broken at 8 the device may be inserted into the header through this end, and in the drawing it is supposed to be so inserted. If this connection is not broken, it may, and usually will be more convenient to remove the cover 8^b and insert it from that end.

I shall now explain the need for a device of the kind I have invented.

After the superheater has been installed it is customary to test it by filling it with water under the desired pressure. If this water is allowed to remain in the elements, there is danger during cold weather of injury to the elements by its freezing. Under such conditions it is therefore desirable to drain the superheater. Moreover if it is not drained, trouble may occur from water hammer.

In some cases the superheater elements are horizontal and then it is usually feasible to arrange the headers so draining is readily accomplished. But in other cases the elements are in a vertical position with the headers at the top, and then draining may not be so readily accomplished. There are at times important advantages in placing the elements vertically and the headers at the top which may make it advisable to retain that arrangement.

With headers of the construction shown in the drawing and presently to be described in some detail, draining of the units is easily effected with my device, no matter what the position of the superheater elements.

The form of headers referred to is the one protected by United States Patent No. 1,363,713, granted to me on December 28th, 1920. A header made according to that patent consists essentially of a pipe 9, and a bar 10, located in the pipe as appears clearly in Figs. 2, 3, and 4, of the present application. Holes 11 extend through the bar and the pipe, the enlarged heads 12 of the elements 4 engaging the outer ends of the holes, and being held in engagement by means of clamps 13. In the form illustrated the clamp does not act directly on the en-

larged heads, but presses against washers 14 which in turn engage the heads. The clamp is pressed against the washers by means of stud-bolt 15 and nut 16, the former extending through the wall of the header and being screwed into the bar 10. 17 is a lock nut, serving also to protect the end of bolt 15.

I shall now describe my improvement which is to be used in connection with super-
10 heaters having headers such as described.

A head, 18, which may be a casting or a forging has its flat face 19 held in engagement with the flat outer face of bar 10 by means of the two compression springs 20. 15 The opposite ends of the springs 20 bear against a forged or cast shoe 21, which bears against the opposite inner side of the pipe 9. The screws 22 serve to guide the springs 20 and the shoe 21 as well as to limit the 20 outward motion of the latter when the apparatus is withdrawn from the header. Two flanges, 23-23, of head 18 engage the two sides of bar 10. The interior of the head 18 is hollow, the hollow being pref-
25 erably of about the width of the holes 11, and extending to the flat face 19. A threaded opening from this interior has screwed into it the pipe 24, which extends in a direction parallel to the axis of the 30 header. The size of the hollow is preferably such that it covers one or at most two of the holes 11, at any one time. The pipe 24 is connected with a compressed air supply (not shown) and at the same time serves to 35 move the apparatus longitudinally in the header, so as to bring it successively into registry with all of the holes 11.

In explanation of the use of my device the following may be said. If the super-
40 heater elements are for the reason spoken of above or from any other cause filled or partly filled with water, and it is desired to remove this water before firing up, the connection to one of the headers is opened, 45 as at flange 8 (or, if desired, at flange 8^b) and the implement inserted. If only one of the headers is supplied with a drain 7, the implement will be inserted into the header not so supplied. The drain being opened, 50 compressed air is then admitted to pipe 24 and the implement slowly moved along toward the farther end of the header. The springs 20 will keep the flat face in close engagement with the flat face of the bar 10. 55 The compressed air will force the water from each element into the other header, whence it flows out through drain 7. The tubes 4 open into the upper header 3 through

the bar 10 as explained above, and as this bar is at one side of the header above its 60 bottom, and the water forced out of any pipe is only a small amount, this water flows off without filling the header to a point where the water might flow back into elements already blown out.

It is obviously not necessary that the headers should be placed in just the position shown to make my invention available. The bars 10 might equally well be at top or bottom of the headers, and in fact, to adapt 70 the device to headers of some other constructions will require only slight modifications.

While I speak above only of compressed air as being used for the purpose of blowing 75 out the elements, it is evident that some other gas, including steam, may be used.

Where it is desired to use my invention to wash out a superheater or other structure of this general description, the fluid used 80 may be water or any desired solution or mixture.

What I claim is:

1. In a superheater comprising two horizontal tubular headers and tubular superheater elements whose two ends are secured each to one of the headers and open into the header above its bottom and portions of which are entirely below their ends; the combination of said headers and elements; 90 a hollow blower head having a face adapted to seat against the openings of the element ends in one of the headers; resilient means forcing the head toward said openings and engaging the opposite inner wall of the 95 header; and means to bring the head successively into seating engagement with said openings and to supply fluid under pressure to it.

2. In a superheater of the class described, 100 the combination of a pipe; a bar extending longitudinally in it and secured to its wall, the pipe and bar having registering holes through them adapted for the attachment of superheater elements; a hollow head 105 adapted to slide longitudinally on the bar; resilient means bearing on the head and on the opposite wall and keeping the head in engagement with the bar; the hollow in the head extending to the face in engagement 110 with the bar so that as the head slides along the bar its interior communicates successively with the openings in the bar; means to move the head along the bar and to supply fluid under pressure to its interior.

BENJAMIN BRODO.
